UNITED STATES PATENT OFFICE.

CLARENCE LILE, OF GRANITE CITY, ILLINOIS.

CHEWING-GUM PACKAGE.

1,132,781.

Specification of Letters Patent.

Patented Mar. 23, 1915.

Application filed May 1, 1914. Serial No. 835,689.

To all whom it may concern:

Be it known that I, CLARENCE LILE, citizen of the United States, residing at Granite City, in the county of Madison and State of Illinois, have invented certain new and useful Improvements in Chewing-Gum Packages, of which the following is a full, clear, and exact description, reference being had to the accompanying drawings, forming a part hereof.

My invention has relation to improvements in chewing-gum packages; and it consists in the novel construction of package more fully set forth in the specification and pointed out in the claims.

In the drawings, Figure 1 is a perspective of a chewing-gum package to which my invention is applied: Fig. 2 is a perspective of the package with one end open; Fig. 3 is a transverse longitudinal middle section of the wrapper, the sticks of gum being left in elevation, the ends of the package being shown closed; Fig. 4 is a similar section showing the starting strip partly pulled out and the gum sticks partially withdrawn; and Fig. 5 is a cross-section on the line 5—5 of Fig. 3, the chewing-gum sticks being shown in end view.

The present invention though shown specifically applied to chewing-gum packages, is not restricted thereto, and may be used in connection with any wrapper in which are packed individual sticks of any commodity, such as candy, cakes, confections, and the like.

The object of the invention is to provide means which will allow for a ready seizure and withdrawal of the contents of the package, once the sealed end of the wrapper has been broken. The advantages of the invention will be fully apparent from a detailed description thereof, which is as follows:

Referring to the drawings, *a, a*, represent a series of sticks of chewing-gum with their individual wrappers, the same being packed side by side in the conventional wrapper 1, the ends of which are formed into folds *h* sealed against the ends of the sticks as well understood in the art. The free longitudinal edges of this wrapper are overlapped and pasted together, thus forming a lapped seam *e* as is common in this class of wrappers. About the wrapper 1 is wrapped an outer wrapper 2 usually carrying reading and advertising matter indicating the brand or flavor of the gum contained in the pack-

age. The foregoing features are well known and form no part of my improvement.

In the present embodiment of my invention I insert between the last gum stick of the series (on the side opposite the seam *e*) and the adjacent wall of the wrapper 1, a card-board or equivalent strip 3, the ends of the strip being folded so as to form flaps 3' 3' which are brought against the ends of the sticks *a*, and between said ends and the sealed folds *h* of the wrapper (Fig. 3). The free edge of the flap 3' is easily detected by the thumb nail, which being inserted against the wrapper 1, immediately beneath the flap 3' (Fig. 1) can readily break through the wrapper and lift the flap 3' as shown in Fig. 2. The flap 3' does not adhere to the sealed folds *h* and can be readily seized (once the package is broken open) and pulled outwardly.

It is obvious that there is more or less friction between the strip 3 and its adjacent stick *a*, as well as more or less friction between the several sticks. There is also considerable friction between the flap 3' at the end not broken into; and when a draft is exerted upon the unfolded or exposed flap 3' (Fig. 4) the friction between the strip 3 and the sticks *a*, and between the ends of the sticks *a* and the flap 3' left undisturbed, will drag the sticks *a* into a step-like formation, the concealed flap 3' (the bottom one in Fig. 4) tending to lift the sticks out of the wrapper 1. The conjoint action of the friction between the several parts as described will thus dispose the sticks in such manner that the stick *a* next to the strip 3 may be singled out and seized between the thumb and forefinger and abstracted without disturbing the remaining sticks. After one stick *a* is removed, this leaves the remaining sticks loose in their package after which their successive removal becomes an easy matter. With the removal of the first stick 100 *a* the starting strip 3 may be wholly pulled out and thrown away.

I do not wish of course to limit myself to a cardboard starting strip 3, nor to any particular width of strip, any device having the characteristics described being contemplated by my invention. I might for example reduce the width of the member 3 so as to convert it into a mere cord when it might still subserve its legitimate purpose. The 110 invention while entitled as an improvement in chewing gum packages, is to be considered

2
 broad enough to cover all packages to which the starting strip may be applied. The object of placing the strip 3 opposite the seam *e* is to prevent said strip from adhering to the seam, the lapped portions whereof are cemented by suitable adhesive to which the strip might accidentally adhere. The flap 3' or its equivalent, possesses the additional advantage in that it serves to sever or shear the folded terminal of the wrapper 1 or that represented by the folds *h* from the body of the wrapper, thereby instantly exposing the ends of the sticks *a*. To accomplish this however, the flap must practically be coextensive with the terminal areal dimension of the package.

Having described my invention, what I claim is:—

1. In combination with a package comprising an outer sealed wrapper and an inner series of articles engaging one another, a member interposed between a terminal article of the series and the adjacent wall of the wrapper, said member having one end maintained in close contact with the sealed portion of the wrapper and between said sealed portion and the articles aforesaid, the breaking of the wrapper at the seal permitting the seizing of the end of the member aforesaid and the subsequent withdrawal of said member, for the purpose set forth.

2. In combination with a package comprising an outer sealed wrapper and an inner series of articles packed side by side and having their terminals covered by the sealed ends of the wrapper, a strip interposed between a terminal member of the series of articles and the wall of the wrapper and terminating in flaps folded against the ends of the articles and confined between said ends and the sealed terminals of the wrapper and maintained in close contact with said terminals, whereby upon the breaking of the wrapper one of the flaps may be seized and a draft exerted on said strip to start the articles out of the wrapper.

3. In a package of the character described and provided with a wrapper sealed at one end, a loose member in the wrapper confined wholly within the wrapper in close contact between the sealed end aforesaid and the contents of the package the edge of said member being disposed close to the wrapper walls whereby the member may serve to shear the wrapper walls adjacent the seal with the breaking of the wrapper at a point beneath said member.

In testimony whereof I affix my signature, in presence of two witnesses.

CLARENCE LILE.
